UNITED STATES PATENT OFFICE.

GEORGE A. KOHOUT, OF CHICAGO, ILLINOIS, ASSIGNOR TO KERSTO CORPORATION, OF CHICAGO, ILLINOIS.

AUTOMATIC FURNACE-STOKER.

1,222,109.

Specification of Letters Patent. Patented Apr. 10, 1917.

Application filed April 30, 1915. Serial No. 24,943.

To all whom it may concern:

Be it known that I, GEORGE A. KOHOUT, a citizen of the United States, residing at Chicago, in the county of Cook and State of Illinois, have invented a certain new and useful Improvement in Automatic Furnace-Stokers, of which the following is a full, clear, concise, and exact description, reference being had to the accompanying drawings, forming a part of this specification.

My invention relates to automatic furnace stokers and has for its object the provision of a new and improved structure for automatically periodically feeding fuel to a furnace. The structure furthermore is of such character that it secures an even distribution of the fuel throughout the grate surface.

In one form of the structure I utilize a deflector plate or surface in the path of the fuel as it is thrown into the furnace.

I provide certain mechanism to throw the fuel, and then I provide certain measuring mechanism which preferably deposits different quantities of fuel in front of the throwing device as to change thereby the distance that the fuel is thrown, thus to deposit it *separatim* over the near and far portions of the grate.

I provide suitable agitating devices to prevent clogging of the fuel and I provide improved mechanism for throwing the deposited fuel into the fire.

I will explain my invention more in detail by referring to the accompanying drawings illustrating one embodiment thereof, in which—

Figure 1 is a side view partially in section of my device as applied to a furnace;

Fig. 2 is a top view of the mechanism showing the furnace walls in section;

Fig. 3 is an enlarged view similar to Fig. 1 illustrating details of construction;

Fig. 4 is a sectional view on line *a* of Fig. 2;

Fig. 5 is a front view of the structure, a portion thereof being in section along line *b* of Fig. 6, and

Fig. 6 is a top view of the mechanism, a portion thereof being in section along line *c* of Fig. 5.

Referring more particularly to the drawings, I show a furnace 1 having a grate 2, an ash door 3 and the customary firing door

4. My improved device is mounted in place in the furnace as thus illustrated, only a small part of the door being cut-away to permit of the entrance of the feeding structure. The structure is, as is apparent from the illustrations, entirely self-contained and mounted upon the furnace by means of the bolts 5, 5.

Referring particularly to Fig. 1, it is seen that this stoker has at its forward extremity a deflecting plate 6 against which the fuel is thrown, thence to rebound along the dotted lines shown in Fig. 2 to its place upon the grate bars 2. The stoker comprises also a large hopper 7 which is continually full of fuel. Within the hopper or rather the lower portion thereof I provide a plurality of agitators 8 suitably mounted upon a shaft 9 and driven from the main driving shaft 10 in any suitable manner. The hopper 7 is closed at its lower extremity by rotatable feeding plates 11 which are mounted upon a counter-shaft 12. A flat plate 13 is interposed between the feed disks 11 so as to form pairs of pockets 14, 15.

It will be seen more particularly by referring to Figs. 4 and 5 that while the pockets of each pair are of the same size preferably, the pockets of another pair are of a different size. It will be understood likewise that while there may be shown only two pairs of pockets that more pairs may be used. The object of making the pockets of unlike size is to supply different quantities of fuel to the projector or throwing device, thus to throw the fuel to the far or near portions of the grate as may be desired.

The measuring disks 11 as stated are mounted upon a shaft 12 and this shaft carries a bevel gear 16 suitably driven by its companion bevel gear 17 which is mounted upon the drive shaft 10. The feeding disks thus continually pass different quantities of fuel through the structure and deposit them within a cylinder 18 also forming part of the stoker structure. Within this cylinder 18 is mounted a piston 19 preferably hollow but having a closed head 20. This piston is periodically moved back and forth within the cylinder by mechanism presently to be described, this piston having a recoil mounting thereby to project, throw or catapult the deposited fuel out of the

left hand extremity of said cylinder (Fig. 4) against the deflector plate 6, from there to be distributed over the grate. The fuel as it passes from the pockets into the cylinder 5 passes through a chamber 21 within which a suitable agitator 22 is rotatably mounted. This agitator is suitably driven by the chain 23 as is readily apparent from the illustrations.

10 The piston 19 has fixedly secured to it a transverse stem 24 slideable within grooves 25 provided in the cylinder walls. This stem is rigidly fastened at its opposite extremities to two plates 26, 26, which plates carry 15 rollers 27 slideable in grooves 28. These plates are each provided with teeth 29 and 30 respectively adapted to be engaged by pins 31 and 32 carried by driving disks 33. The driving disks 33 are suitably mounted 20 upon the driving shaft 10 and when they are rotated engage successively through the agency of their pins 31 and 32 the teeth 29 and 30, thus to slide the plates 26 and their attached piston 19 to the right hand extremity of its stroke (Figs. 3 and 4). Immediately the pin 32 releases itself from the tooth 30, springs 34 come into play to violently project the piston 19 to the left (Figs. 3 and 4), thus to discharge the fuel deposited 25 within the cylinder. A buffer plate 35 is provided to relieve the structure from shocks.

As will be seen the deflecting plates 6 are universally adjustable by means of their pivotal mounting 36 upon a pivotally mounted stud 37. These studs 37 are then rotatably mounted upon brackets 38, which brackets are fixedly secured to the structure by the set screws 39. The double pivotal mounting thus provides a practically universal adjustment. The deflecting or baffle plates 6 are thus capable of universal adjustment so as to vary the length of throw and also to vary the distribution over the grate.

45 It will of course be understood that the auxiliary crusher 40 which is mounted within the hopper 7 may be used to crush the fuel should such be found necessary. The driving shaft 10 which controls the operations of the entire device may be suitably connected to an engine or motor whose speed of operation may be proportional for instance to the steam pressure or other variable function as may be desired, thus to render the operations of the device practically automatic in accordance with the requirements of the furnace.

From what has been thus described the nature of my invention will be readily clear to those skilled in the art. Having however thus described one form which my invention

may take, what I claim as new and desire to secure by Letters Patent is:

1. An automatic stoker having a fuel reservoir, a charge receptacle, movable means for feeding fuel from said reservoir to said charge receptacle, said feeding means including a plurality of different sized pockets, a piston for discharging said fuel from said charge receptacle, and a universally adjustable deflecting plate in the path of said discharged fuel. 65 70

2. An automatic stoker having a fuel reservoir, a charge receptacle, movable means for feeding fuel from said reservoir to said charge receptacle, said feeding means including a plurality of different sized pockets, a spring controlled piston for discharging said fuel from said charge receptacle, and a universally adjustable deflecting plate in the path of said discharged fuel. 75 80

3. An automatic stoker having a fuel reservoir, a charge receptacle, movable means for feeding fuel from said reservoir to said charge receptacle, said feeding means including a plurality of different sized pockets, spring controlled means for discharging said fuel from said charge receptacle, and a universally adjustable deflecting plate in the path of said discharged fuel, said spring controlled means including a piston, recoil springs for said piston, a cam plate movable with said piston, and driving means for actuating said cam plate. 85 90

4. An automatic stoker having a fuel reservoir, a charge receptacle, means for feeding different predetermined amounts of fuel from said reservoir to said receptacle, a piston for discharging said fuel from said receptacle, and a deflecting plate in the path of said discharged fuel. 95 100

5. An automatic stoker having a fuel reservoir, a charge receptacle, means for depositing different predetermined amounts of fuel from said reservoir to said charge receptacle, and a piston having a uniform stroke for discharging said fuel from said charge receptacle, the distance of throw depending upon the amount of deposited fuel. 105

6. An automatic stoker having a fuel reservoir, a charge receptacle, movable means for feeding fuel from said reservoir to said charge receptacle, said feeding means including a plurality of different sized pockets, and a piston for discharging said fuel from said charge receptacle. 110 115

In witness whereof, I hereunto subscribe
my name this 27th day of April, A. D., 1915.
GEORGE A. KOHOUT.
